UNITED STATES PATENT OFFICE.

CHARLES H. SPENCER, OF CHICAGO, ILLINOIS.

DESIGN FOR A BADGE, PENDANT, OR LIKE ARTICLE OF JEWELRY.

52,997.

Specification for Design.

Patented Feb. 11, 1919.

Application filed November 15, 1918. Serial No. 262,725. Term of patent 7 years.

To all whom it may concern:

Be it known that I, CHARLES H. SPENCER, a citizen of the United States, residing at Chicago, in the county of Cook and State of Illinois, have invented a new, original, and ornamental Design for a Badge, Pendant, or like Article of Jewelry, of which the following is a specification, reference being had to the accompanying drawing, forming part thereof.

In the drawing—

Fig. 2 is a vertical section thereof on the line 2—2 of Fig. 1.

I claim:

The ornamental design for a badge, pendant or like article of jewelry, as shown.

CHARLES H. SPENCER.
